US00D738029S

(12) **United States Design Patent**
Obana et al.

(10) **Patent No.:** **US D738,029 S**
(45) **Date of Patent:** **** Sep. 1, 2015**

(54) **MODULAR UNIT**

(71) Applicant: **Sony Corporation**, Tokyo (JP)

(72) Inventors: **Bunichi Obana**, Kanagawa (JP); **Hideki Fujita**, Kanagawa (JP); **Hideaki Tachino**, Kanagawa (JP); **Hiroki Oka**, Kanagawa (JP); **Nobuyuki Yokosawa**, Saitama (JP)

(73) Assignee: **Sony Corporation**, Tokyo (JP)

(**) Term: **14 Years**

(21) Appl. No.: **29/483,631**

(22) Filed: **Feb. 28, 2014**

(51) **LOC (10) Cl.** **26-99**

(52) **U.S. Cl.**

USPC **D26/113**

(58) **Field of Classification Search**

USPC D26/9, 10, 12, 13, 15, 16, 24, 51, 61, D26/72, 76, 80, 81, 85, 86, 88, 90, 113, 118, D26/119, 120, 122, 128, 129, 138, 143,

(57) **CLAIM**

The ornamental design for a modular unit, as shown and described.

DESCRIPTION

FIG. 1 is a perspective view of a first embodiment of a modular unit showing our new design;

FIG. 2 is a front elevation view thereof;

FIG. 3 is a right side elevation view thereof;

FIG. 4 is a left side elevation view thereof;

FIG. 5 is a top plan view thereof; and

FIG. 6 is a bottom plan view thereof.

FIG. 7 is a perspective view of a second embodiment of a modular unit showing our new design;

FIG. 8 is a front elevation view thereof;

FIG. 9 is a right side elevation view thereof;

FIG. 10 is a left side elevation view thereof;

FIG. 11 is a top plan view thereof; and,

FIG. 12 is a bottom plan view thereof.

The broken lines illustrate unclaimed portions of the modular unit and form no part of claimed design.

1 Claim, 10 Drawing Sheets
